WINDOW BLIND

Raymond C. Pratt, Chicago, Ill., assignor to H. B. Dodge and Company, Chicago, Ill., a corporation of Illinois

Application May 21, 1936, Serial No. 31,000

18 Claims. (Cl. 156—17)

This invention relates to window blinds, more particularly blinds of the transverse slat type.

The invention has for an object the provision of a window blind having transverse slats extending wholly or partly across the window and fixed in position adjacent the window, the slats thereof being held securely against accidental displacement but being readily removable for cleaning or the like.

10 Another object of this invention is in the provision of improved supporting means and slats so constructed and arranged that only a minimum of standardized parts must be kept in stock in order to readily install a window blind of any 15 general size or outline.

A further object of the invention is the provision of a window blind having a plurality of removable slats so arranged to give the greatest ornamental effect to the window, permit removal 20 ability of the slats from their supports, provide for the proper illuminating effect with respect to the position of the slats, and allow for easy and instant removal of the slats for cleaning purposes and otherwise, as well as to permit ready erection 25 of the slats in place.

These objects and other objects which will hereinafter appear are obtained by the novel construction, arrangement, and combination of elements hereinafter described and claimed.

30 A window blind and support therefor embodying the present invention is illustrated in the accompanying drawings in which—

Fig. 1 is a view in elevation of a blind constructed in accordance with the present invention;

Fig. 2 is an enlarged sectional view of a portion of the blind and supporting means of Fig. 1 on line 2—2 of Fig. 1;

Fig. 3 is an enlarged view in perspective of one 40 of the supporting members or clips and the base with which such member is used;

Fig. 4 is an enlarged view in perspective of the supporting member or clip shown in Fig. 3 apart from the base member;

45 Fig. 5 is a sectional view through the base member and supporting member of Fig. 3 on line 5—5 of Fig. 3;

Fig. 6 is a view in perspective of a portion of one of the window slats showing an aperture therethrough to cooperate with part of the supporting means;

Fig. 7 is a view similar to that of Fig. 2, but illustrating a slightly modified form of the device embodying the invention;

55 Fig. 8 is a detail view similar to Fig. 1, but

showing the slats supported in a different position;

Fig. 9 is a detail sectional view showing the manner in which the slats are supported;

Fig. 10 is a detail perspective view of one of the 5 slat supporting members in its channel support; and

Fig. 11 is a detail perspective view of the slat supporting member.

The embodiment shown for illustrative purposes is formed of a series of transverse slats which are intended to form a more or less permanent part of the decoration of the room in which they are situated. Referring to the drawings, and particularly to Figs. 1 to 7 thereof, 15 there is shown a blind which comprises a plurality of long slats 10 (Fig. 1) mounted within a window frame 11, and below the long slats groups of shorter slats 12 which extend only part way across the window, leaving an opening at the 20 center of the window. The slats are carried on series of supports or arms 13 which extend upwardly into the room at an angle of fifty or sixty degrees from the horizontal. Each slat generally is parallel to each other slat.

As shown in Fig. 2 each arm 13 is one arm of a substantially V-shaped member 14. Another arm 15 of the V-shaped member is adapted to lie within a channel or base member 16 which provides a base for supporting the members 14 in 30 position, usually with the arms 15 vertical and the arms 13 extending away therefrom into the room. At the top of each arm 15 a bent tab 17 provides a platform upon which the bottom of the V-shaped member 14 next above will rest 35 when the members are inserted in the channel 16.

Above the top surface of the arm 13 is a tongue 18 which extends first away from the arm 13 and then substantially in the same direction 40 as arm 13. The slat 10 or 12 is provided with a hole 19 adapted to receive the tongue 18.

Just above the junction of arms 13 and 15 the material of arm 15 is bent inwardly toward arm 13 in a loop 20 which serves to resist the 45 possible movement of the lower edge 21 of the slat 12 so that the slat can not be removed from the tongue 18 by rotating the edge 21 upward, but only by moving the slat longitudinally of the arm 13 while at the same time lifting the entire 50 slat.

The V-shaped member 14 is secured in the channel 16 by projections or keys 22 which engage beneath the inwardly turned edges 23 of the channel 16.

In the form of device shown in Figure 7 a modified slat 24 is used, comprising a top facing 25, an under body 26, and a metal sheath 27. The facing 25 provides an unbroken surface which 5 may be painted or otherwise decorated. The modified slat 24 is used with a V-shaped member 28 similar in every respect to the V-shaped member 14 except that its tongue 29 may be shorter than tongue 18 and may be straight. 10 A hole in under body 26 receives tongue 29. A corresponding hole through sheath 27 has its upper wall protruding below the upper wall of the hole through the under body 26 and provides a catch to prevent accidental displacement of 15 the slat. Also since the slat 24 may be thicker than the slat 12 the loop 30, corresponding to the loop 20 in the V-shaped member 14, is further removed from the slat supporting arm 31, corresponding to the arm 13. The other parts of the 20 modified member 28 are the same as in the member 14 first described.

Two or more channel members 16 are secured within a window frame 11 in any desired manner, as for instance by the use of screws 32 which 25 may extend into the window frame or into blocks secured to the window frame. Alternatively angle irons may be used, secured to the window frame and to the channel member 16, or the end of the channel member itself may be bent over 30 and used as an angle iron. At the bottom of each channel member 16 an inwardly extending tongue 33 provides a bottom stop to determine the lowermost position of the slats 12. In the window blind illustrated in Figure 1 six channel 35 members 16 are used as is indicated by the six lines of arms 13. In the positions indicated at 34, 35, 36, and 37 the channel members 16 extend from top to bottom of the window and are fastened at both ends. In positions 38 and 39 40 the channel members 16 are secured only at the top of the window and extend there-below only part way across the window. By such arrangement of supports the slats 10 and 12 are firmly supported and are prevented from sagging. 45 The slats once in place on the arms 13 will not be blown off or be accidentally knocked off, but may be readily removed for cleaning the slats or the window by merely lifting them in a general upward direction.

50 The installation of the blind in the window may be made by cutting channel members to the required length, inserting the V-shaped members 14 or 28 into them and fastening them in place within the window frame 11. The slats 10 and 55 12 are then readily placed on the arms 13. The installation may be completed without making up special pieces, as the channel member may be prepared in long pieces and cut to fit the particular needs. The several V-shaped members 14 60 or 28 are completely interchangeable and need not be inserted in the channel members in any particular order, the only requirement being that they be right side up.

In Figs. 8 to 11, inclusive, there is shown a 65 Venetian blind similar in many characteristics to the blind described in Figs. 1 to 7, inclusive, but there is shown a different means for supporting the slats. Instead of deforming the supports or arms 13, as indicated particularly in Fig. 70 4, the supporting arm 13 may be in the form designated generally by the numeral 50, Figs. 9 to 11. Each supporting member or arm 13 comprises a relatively straight or vertical portion 51 which is bent at 52 to provide the inclined portion 53. The straight portion 51 is provided at its

upper surface with a bent-over ledge or flange 54 which acts in all respects for the same purpose as the flange 17 previously described. Projections 55 are formed in the straight portion 51 and co-operate with the supporting channel 16. 5 The projections 55 are substantially the same and are for the same purpose as the projections or keys 22 previously described. The bottom portion 53 of the member designated generally by the numeral 50 is provided with a turned bottom lip 56 to support the lower edge of a slat 57, Fig. 9. A tongue 58, similar to the tongue 18, is struck from the body of the portion 53 and is adapted to engage a hole 59 formed in the slat. There are as many holes 58 provided as may be 10 necessary to receive the projections or tongues 58. The number of supporting members 13, 50 depend upon the width of the window opening and the number of supporting channels 16.

The method of supporting the slats shown in 20 Figs. 8 to 11, inclusive, is very similar in all respects to the method of supporting the slats previously described. However, in Figs. 1 to 8 the slats are shown in one position, while in Figs. 8 to 11, inclusive, they are shown inclining downwardly instead of upwardly. The slat suspension means shown in Figs. 8 to 11, inclusive, is often preferable where flood lights are used in the window. The slats cause the light to be properly diffused, whereas in the construction 30 shown in Figs. 1 to 8, particularly in Fig. 2, the rays of light from the flood lights would pass through the slats and illuminate the sidewalk outside. The invention therefore contemplates the removable suspension of slats and the supporting of slats in the various horizontal but inclined positions depending upon the dressing of the window or whether or not the flood lighting system is employed.

This invention thus results in an improved 40 window blind of wide, convenient, and economical applicability. It is to be understood that the embodiment disclosed herein is merely illustrative and that many modifications may be made in the device herein disclosed without departing 45 from the true scope of the invention.

What is claimed as new and is desired to be secured by Letters Patent of the United States is:

1. Attaching means for window blind slats comprising a channel member fixedly secured 50 with respect to the window, and clips seated removably in said channel and removably supporting the slats.

2. In a support for a window blind slat, a base member, and a clip comprising a strap of metal 55 having a leg adapted to engage the base member for support thereby, and a leg extending at an angle to said first leg, said second leg having a tongue extending from the face thereof opposite said first leg.

3. A clip for supporting a window blind slat and adapted for co-operation with a base member, comprising a strap of metal having a leg adapted to engage the base member for support thereby, and a leg extending at an angle to said 65 first leg, said second leg having a tongue extending from the face thereof opposite said first leg and in the same general direction as said second leg.

4. In combination, a base member, a clip for 70 co-operation with the base member comprising a V-shaped strap of metal having a leg adapted to engage said base member for support thereby and a leg extending at an angle to said first leg, said second leg having a tongue extending from 75

- the face thereof nearest said first leg and in the same general direction as said second leg, and a slat having an aperture therein adapted to receive and hook over said tongue.
5. In combination, a base member, a clip for co-operation with the base member comprising a V-shaped strap of metal having a leg adapted to engage said base member for support thereby and a leg extending at an angle to said first leg, 10 said second leg having a tongue extending from the face thereof nearest said first leg and in the same general direction as said second leg, said first leg having a loop extending toward the second leg and narrowing a portion of the space 15 between the first and second legs, and a slot having an aperture therein adapted to receive said tongue and hook thereover, the movement of the bottom edge of said slat being restricted by said loop to prevent accidental displacement 20 of said slat from said tongue.
6. A clip for supporting a window blind slat and adapted for cooperation with a base member, comprising a generally V-shaped member having one leg thereof adapted to removably 25 engage the base member for support thereby and the other leg having means thereon to removably engage the window blind slat, the first named leg being bent inwardly in a loop at a point near the junction of the two legs whereby to additionally restrict movement of the slat.
7. In combination, a base member, a clip for cooperation with the base member and supported thereby and having a leg with a tongue extending from the upper surface thereof, and a slat adapted to fit on the upper surface of said leg 30 and about said tongue.
8. A slat for a window blind, comprising an imperforate top facing, an under body having an aperture therein, and a metal sheath about said under body and having an aperture corresponding with the aperture in said under body.
9. A slat for a window blind, comprising an imperforate top facing, and an apertured under body.
- 40 10. A window blind comprising an elongated support, slat supporting means removably secured to said support, said slat supporting means having a rigid, inclined supporting surface extending outwardly from said support, and slats removably positioned on the inclined supporting 45 surface and residing substantially flatwise thereof for support thereby.
11. A window blind comprising a support, a clip member removably mounted in said support, a slat, an inclined arm on said clip for supporting the slat, said slat having a hole provided therein, and a tongue on the inclined arm and adapted to be received in said hole in the slat to support the slat.

12. A blind comprising a supporting channel, a clip slidably mounted in the channel, an arm extending at an angle from the clip and integral therewith, a slat supported on the arm, and interfitting means between the slat and the arm to support said slat.

13. A blind comprising a supporting channel, a clip slidably mounted in the channel, an arm extending at an angle from the clip and integral therewith, a slat supported on the arm, 10 interfitting means between the slat and the arm to support said slat, and a ledge turned from the end of the arm and adapted to support and engage the lower side edge of a slat.

14. In a window blind, a longitudinally extending channel member, a clip member slidably supported by said channel member for movement longitudinally thereof, a projecting portion on said clip having slat supporting means thereon, and a slat having a portion engaging said supporting means to support the slat.

15. In a window blind, a longitudinally extending base member, a clip slidably supported by said base member for free movement longitudinally thereof, said base member restraining 25 the clip laterally with respect to the base member, a laterally extending portion on said clip providing slat supporting means, and a slat having a portion engaging said slat supporting means whereby to support said slat on the clip.

16. In a window blind, a substantially vertically extending channel member, a plurality of clips slidably supported by said channel member for sliding movement longitudinally thereof, said clips being arranged in stacked relationship in 35 the channel member, engaging means on each clip, and means on each adjacent clip to cooperate with said engaging means whereby to support and position each superposed adjacent clip longitudinally with respect to the channel member.

17. In a support for a window blind slat, a base member comprising a channel and a clip comprising a strap of metal having a leg slidably mounted in the channel and residing generally longitudinally thereof for support thereby, and a leg extending at an angle to said first leg for supporting the slat.

18. In a support for a window blind slat, a base member, and a clip comprising a generally V-shaped member having one leg thereof adapted to removably engage the base member for support thereby and the other leg having means thereon to removably engage the window blind slat, the first named leg having a portion extending inwardly at a point near the junction of the two legs whereby to additionally restrict movement of the slat.

RAYMOND C. PRATT.
